CAN OPENER

Thomas Leo Lane, Petaluma, Calif.

Application September 28, 1953, Serial No. 382,569

5 Claims. (Cl. 30—6.1)

1

This invention relates to a can opener and more particularly to a fixedly mounted can opener in which a can is inserted and opened by movement of the can.

An object of this invention is to provide a can opener in which a metal can may have the top perforated by sliding the can inwardly relative to the supporting base.

Another object of this invention is to provide a can opener having a pivoted perforating member on a base which is actuated by a sliding movement of a can supporting member.

A further object of this invention is to facilitate the perforation of sealed cans of liquid contents.

A still further object of this invention is to provide a can opener wherein the can is at all times maintained in a vertical position to avoid spilling of the contents upon opening thereof.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the can opener forming the subject of this invention;

Figure 2 is a top view of the preferred form of the present invention;

Figure 3 is a vertical sectional view of the preferred form of the present invention showing the can puncturing plate in raised position;

Figure 4 is a vertical sectional view similar to Figure 3 with the can puncturing plate shown in its lowered position; and

Figure 5 is a sectional view taken substantially along the section line 5—5 of Figure 2.

Referring now more specifically to the accompanying drawings, it will be seen that the improved can opener forming the subject of this invention includes, as shown in Figure 1, a mounting bracket 10 which is adapted to be fixedly secured to a vertical support and a can support 12.

The bracket 10 is provided with a first pair of rails 14 extending perpendicular thereto. The rails 14 are formed of a U-shaped channel member with the openings 16 in the rails 14 facing toward one another. The other ends of the rails are sealed as at 18. Suitable braces 20 are mounted between the rails 14 and the bracket 10 rigidly securing the rails in position.

A second pair of rails 22 are mounted on the bracket 10 above the rails 14. The rails 22 are

2

rigidly held in position by braces 24. The rails 22 are formed of U-shaped channel members having openings 26 therein facing each other. The outer ends of the rails 22 are joined together and sealed by a plate 28. Rails 22 extend at an angle downwardly from the brackets 10 toward the rails 14.

The can support 12 comprises a bottom plate 30 upon which a can 32 will rest and an upwardly extending wall 34. Wall 34 is shaped to conform with the contour of the wall of a can 32 when the can is placed in position on the support. A pair of rollers 36 are mounted on the wall 34 at diametrically opposite points near the top of the wall. The rollers 36 are mounted in the openings 16 in the rails 14 and permit the can support to be moved toward and away from the bracket 10.

A vertically extending longitudinal member 38 is secured to the rear of wall 34 adjacent the midpoint thereof. The member 38 extends above the wall 34 and is provided with a bifurcated end 40. A link 42 is pivotally secured at its midpoint to member 38 at the bifurcated end 40 thereof. A can puncturing plate 44 having a pair of ears 46 secured to the top thereof at the center is pivotally mounted on one end of the link 42 by means of a pin 48 extending through the ears 46 and the link 42. The lower surface of the can puncturing plate 44 is provided with a pair of sharp projections 50 at diametrically opposite points thereon.

A pair of rollers 52 are mounted on opposite sides of the other end of link 42. The rollers 52 are received in the openings 26 in the rails 22.

In practical use, a can is mounted on the support 12 and the can and the support are moved in a direction toward the bracket 10. As the support 12 moves rearwardly link 42 will be caused to move about the pivotal connection to the support 12 thereby causing the projections 50 to puncture the top of the can. The plate 44 is urged downwardly due to the rollers 52 riding up along the rails 22. After the can has been punctured movement of the support 12 and the can away from the bracket will cause the plate 44 to be raised thereby allowing easy removal of the can from the support. The rollers 36 and 52 will be prevented from separating from the rails 14 and 22 by means of the members 18 and 28 respectively.

From the foregoing, the construction and operation of the device will be readily understood and further explanation is believed to be unnecessary. However, since numerous modifications

and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. A can opener comprising a bracket adapted to be secured to a vertical support, a first pair of parallel rails secured to said bracket and extending perpendicular thereto, a can support mounted for sliding movement on said first rails, a second pair of rails secured to said bracket above the first pair of rails, a can puncturing plate, means for connecting said can puncturing plate to said can support and said second pair of rails.
2. A can opener comprising a bracket adapted to be secured to a vertical support, a first pair of parallel rails secured to said bracket and extending perpendicular thereto, a can support mounted for sliding movement on said first rails, a second pair of rails secured to said bracket above the first pair of rails, a can puncturing plate, means for connecting said can puncturing plate to said can support and said second pair of rails, said can support having a pair of rollers extending outwardly from the sides thereof at diametrically opposite points, said first rails comprising a pair of channel members having their openings facing toward each other, said rollers being received in the openings in the channel members.
3. A can opener comprising a bracket adapted to be secured to a vertical support, a first pair of

parallel rails secured to said bracket and extending perpendicular thereto, a can support mounted for sliding movement on said first rails, a second pair of rails secured to said bracket above the first pair of rails, a can puncturing plate, means for connecting said can puncturing plate to said can support and said second pair of rails, said can support having a pair of rollers extending outwardly from the sides thereof at diametrically opposite points, said first rails comprising a pair of channel members having their openings facing toward each other, said rollers being received in the openings in the channel members, said second pair of rails being comprised of channel members having openings therein facing each other, said second rails extending downwardly at an angle from the bracket toward the first pair of rails.

4. The combination of claim 3 wherein said means for connecting the can puncturing plate to the can support and the second pair of rails comprises a link pivotally secured adjacent its midpoint to the top of the can support, said can puncturing plate being pivotally secured to one end of said link and a pair of rollers mounted on opposite sides of the other end of said link, said rollers being received in the openings in the channels of the second pair of rails.

5. The combination of claim 4 wherein said can puncturing plate is provided with a pair of downwardly extending projections at diametrically opposite points.
